UNITED STATES PATENT OFFICE.

B. F. KOLLER, OF SHREWSBURY, PA., ASSIGNEE OF SAMUEL GIBSON.

IMPROVED SCRUBBING-BRUSH.

Specification forming part of Letters Patent No. 82,705, dated October 6, 1868; Reissue No. 3,773, dated December 21, 1869.

To all whom it may concern:

Be it known that SAMUEL GIBSON, of Safe Harbor, in the county of Lancaster and State of Pennsylvania, did invent certain new and useful Improvements in Scrubbing-Brushes; and I do hereby declare that the following is a full, clear, and exact description thereof, reference being had to the accompanying drawings, and to the letters of reference marked thereon.

The nature of this invention consists in the construction of a scrubbing-brush, in which the ordinary bristle-brush is combined with strips of rubber, and all are fastened together by means of a keeper, as will hereinafter be more fully described.

In order to enable others skilled in the art to which this invention appertains to make and use the same, I will now proceed to describe its construction and operation, referring to the annexed drawings, which form a part of this specification, and in which—

Figure 1 is a perspective view; Fig. 2, a longitudinal view; Fig. 3, a plan view; Fig. 4, a bottom view of the holder; Fig. 5, a side view of the clamp or keeper, and Fig. 6 a side view of the bristle-brush.

A represents the holder, which consists of a bar of metal provided with a handle, bent in the usual mode for scrubbing-brushes, and forming a socket in which the wooden handle is inserted. Between this holder and the clamp or keeper E, one, two, or more strips of rubber, D D, are inserted and fastened by means of two ordinary screws, E' E', as shown in Fig. 2. Said screws, compressing the keeper E and holder A, retain the rubber strips in any position desired, whether high or low.

On the lower side of the holder, and by the same screws, is attached an ordinary-made scrubbing-brush, C, having one or more rows of bristles. Said brush, having two or more

screw-holes, as shown in Fig. 6, can be raised or lowered at will, so that by raising the bristle part of the brush the rubbers D D will act independently as a drier.

On the upper side of the keeper E an ordinary brush, with two or more rows of bristles, may be attached by the same screws E' E' which hold the rubber and brush C together, which may be used as an ordinary scrubbing-brush.

The wooden handle O is attached by having near its end a common screw or pin, M, fitting in a slot, S, on the handle of holder A.

The operation of this improvement is as follows: The rubber and brush being fastened so that the bristles and rubbers are even, the bristles carry the water with them, the rubber acting as a drier. By taking out the handle, which by its simple fixing is done in a moment, the instrument can be used as a hand-brush.

Having thus described the invention of S. GIBSON, what I desire to secure by a reissue of his Letters Patent is—

1. Attaching a strip of rubber to one side of a long-handle scrubbing-brush so that it will be parallel with the rows of the bristles thereof, substantially as described.

2. In a long-handle scrubbing-brush, the arrangement of the strip of rubber D so as to project from one and the same side of the brush with the bristles thereof, substantially as and for the purpose specified.

3. The arrangement of the shouldered plate A and flanged keeper E, inclosing the strips of rubber D upon the forward part of the bristle brush G, all as herein shown and described.

B. F. KOLLER.
